(57) **CLAIM**

The ornamental design for a display screen or portion thereof with graphical user interface as shown and described.

DESCRIPTION

The file of this patent contains at least one figure executed in color. Copies of this patent in color will be provided by the Office upon request and payment of the necessary fee. FIG. 1 is a front view of a display screen or portion thereof with graphical user interface showing the claimed design; and,

FIG. 2 is another embodiment thereof.

The dashed broken lines in the figures show a display screen or portion thereof and form no part of the claimed design. The dot-dash broken lines and the areas within the dot-dash broken lines in the figures show portions of the graphical user interface that form no part of the claimed design.

The design of an apple with a bite removed and the word “Music,” and the red square with rounded corners with a white design of a two eighth notes at the center, and the words “Apple Music” forming part of the claimed design, are registered trademarks of Apple Inc.
